UNITED STATES PATENT OFFICE.

VICTOR ANGERER, OF RIDLEY PARK, PENNSYLVANIA, ASSIGNOR TO WILLIAM WHARTON, JR., & COMPANY, INCORPORATED, OF PHILADELPHIA, PENNSYLVANIA, A CORPORATION OF PENNSYLVANIA.

SWITCH STRUCTURE.

No. 852,212.

Specification of Letters Patent.

Patented April 30, 1907.

Application filed November 3, 1906. Serial No. 341,883.

To all whom it may concern:

Be it known that I, VICTOR ANGERER, a citizen of the United States, residing at Ridley Park, Pennsylvania, have invented certain Improvements in Switch Structures, of which the following is a specification.

My invention relates to certain improvements in means to prevent cars straddling switches.

The object of my invention is to construct a switch tongue actuating mechanism so that its elements can be set in three positions, namely, that the switch tongue will be thrown to and held only in its normal position at the left of the structure, or thrown to and held in its normal position at the right of the structure, or thrown to and held in either the right or left position; the mechanism being so designed that it will allow the tongue to yield when a car passes over the switch structure from the heel end of the tongue, but will prevent accidental displacement of the tongue.

Referring to the accompanying drawings: Figure 1, is a transverse sectional view through the switch structure and switch box, illustrating my improved mechanism; Fig. 2, is a plan view of the switch box with the cover removed; Fig. 3, is a transverse sectional view on the line 3—3, Fig. 1; Fig. 4, is a perspective view of the rocker illustrated in Fig. 1; Figs. 5 and 6, are perspective views of details of the invention; Figs. 7, 8 and 9, are views of modifications of the invention; Figs. 10 and 11, are diagram views showing the rocker in position so that the switch tongue will normally rest against the left side of the switch structure; Figs. 12 and 13, are views showing the rocker in position so that the switch tongue will normally rest against the right side of the structure; Figs. 14 and 15, are diagram views illustrating the rocker in such a position that the switch tongue will normally rest against either the left or right of the switch structure.

Referring in the first instance to Fig. 1, A is the switch structure having a movable tongue a. The switch structure in the present instance consists of a body portion A' made of cast iron or steel and in some instances may be made of manganese or other hard steel and mounted in a recess in the body portion is a hard metal center piece A²

forming the right and left hand walls a², a' of the cavity in which the switch point a is pivoted. At one side of the switch structure is a box B having a cover B' with a deep flange, as indicated, which rests on a rib b on the interior of the box. On each wall of the box are three sockets c, c', c² for the reception of the rocker D. This rocker is made as clearly shown in Fig. 4, and has two side members and a cross bar d with two sets of hubs d', d², one of the hubs on one side being longer than the others so that there can be no mistake in putting the rocker in its sockets. E is a rod having a projecting point e which extends into a cavity in the under side of the switch tongue a in the present instance, the inner end of this rod is screw threaded and mounted on the screw threaded portion is a head e' which is forked to engage the cross bar d of the rocker D. This head can be adjusted on the arm by turning the nuts e², as clearly illustrated in Fig. 1. The head is illustrated in Figs. 1 and 6, is made in two parts with one or more spacing washers between them, the parts are clamped together on the rod E by the nuts e² and around the cross bar d of the rocker, but the head may be made in one piece as in Figs. 7 and 8. Hung to the cross bar d between the forked members of the head E is a hook F. This hook is screw threaded at its lower end and mounted on the screw threaded portion is a nut f having knife edge pivots f' at each side. These knife edge pivots rest in a notch on the under side of a lever G having a hooked inner end g which rests under a cross bar C firmly secured to the box B. As shown in Figs. 1 and 2, the free end of the lever G is in the form of a box g' in which can be placed any suitable material to be used as a weight to return the parts to their normal position.

It will be noticed that when the hubs d² are in the socket e', as illustrated in Figs. 1, 10 and 11, the normal position of the switch tongue is at the left hand side, as illustrated in Figs. 1 and 10. When the hubs d² are in the sockets c², as illustrated in Figs. 12 and 13, then the normal position of the tongue is at the right hand side. When the hubs d' are in the sockets c, as illustrated in Figs. 14 and 15, then the normal position of the switch tongue is either at the right or left hand side of the structure, as it will be noted

in these figures the weighted lever is down in either case and the cross bar simply shifts from one side of the center to the other, whereas in Figs. 10, 11, 12 and 13, the cross bar does not pass the center line through the pivot of the rocker.

It will be seen that all that is necessary to alter the switch is to lift the rocker out of one set of sockets and set it in either of the other sets of sockets. No additional mechanism is added nor is any mechanism omitted.

The rod E can be longitudinally adjusted in its head e' so as to set the switch point as desired.

In Fig. 7, I have illustrated a modification in which a coiled spring is used in place of the weighted box g' of the lever. The lever G' in this instance is shortened and is forked at its outer end, and passing through the forked portion is a rod g² on which is mounted a spring g³, a telescopic box g⁴ incloses the spring. The rod g² has an eye at its lower end engaging a hook g⁵ projecting from the box. Otherwise the parts are identical with those illustrated in Fig. 1, with the exception that the block e' is made in one piece.

In Fig. 8, I have shown a flat spring G³ bearing upon the lever G², the flat spring rests in a cavity b² in the box and a set screw b³ bears upon the spring so as to place more or less tension upon it, the set screw is carried by a block b⁴ hooked to the side of the box.

In Fig. 9, I have shown an S-hook F' in place of the single hook illustrated in Fig. 1, and the shape of the head e³ of the rod E' is slightly different from that illustrated in Fig. 1. The S-hook F' engages the cross bar d of the rocker D and is hooked onto a bar g⁶ on a weighted lever G³.

Thus it will be seen that if it is desired to provide a tongue switch in which the tongue is normally in the left hand position the rocker is placed in the position illustrated in Fig. 10, the mechanism will hold the tongue against accidental displacement and will return it to its normal position if moved. If the tongue is to be normally in the right hand position then the rocker is placed in the position illustrated in Fig. 12. If a switch is to be provided in which the tongue can be moved from one position into another and held in either position against accidental displacement then the rocker is placed in the position illustrated in Fig. 14.

I preferably so construct and arrange the mechanism that the rocker will move in a vertical arc, but when the springs are used such as shown in Figs. 7 and 8, the mechanism can be arranged horizontally if desired.

I claim:—

1. The combination of a movable switch tongue, means for holding the tongue in its normal position, a rocker connected to the tongue, a series of bearings for the rocker, ar-

ranged so that by changing the rocker from one bearing to another it will return the tongue to normal position in one or the other direction, or hold it in either position, substantially as described.

2. The combination in a switch structure, of a movable switch tongue, means for holding or returning the switch tongue to normal position, a rod extending laterally from the switch tongue, a pivoted rocker and bearings for the reception of the rocker, said rocker being capable of being set in different positions in the bearings and connected to said means from any of these positions, substantially as described.

3. The combination in a switch structure, of a switch tongue, and automatic means for returning said tongue to a predetermined position, including a rod extending laterally from the tongue, a rocker coupled to the rod, bearings for the rocker, a lever, a link connecting the rocker with the lever, and means for applying pressure to the lever by which the tongue is held or returned to its normal position, substantially as described.

4. The combination in a switch structure, of a casing at one side of the structure, bearings in the casing, a movable tongue on the switch structure, a rod extending laterally from the tongue into the casing, a rocker mounted in bearings and coupled to the rod, a lever in the casing, and a link connecting the rocker with the lever, substantially as described.

5. The combination in a switch structure, of a casing attached to one side of the structure, a movable tongue on the switch structure, a rod extending laterally from the switch tongue and into the casing, bearings within the casing, a rocker coupled to the rod and mounted in said bearings so that it will operate through a vertical arc, a weighted lever pivotally mounted in the casing, and a link connecting the rocker to the weighted lever, substantially as described.

6. The combination in a switch structure, of a casing at the side of the structure, bearings in the casing, a pivoted switch tongue mounted on the structure, a rod extending laterally from the switch tongue and into the casing, a head longitudinally adjustable on the rod, a rocker pivoted to the casing and engaging the head, a lever pivoted in the casing, a link connecting the lever to the head, and means for exerting pressure on the lever, substantially as described.

7. The combination in a switch structure, of a movable tongue, a casing at one side of the structure, a rod extending laterally from the switch tongue into the casing, a forked head secured to the rod, a rocker having hubs mounted in sockets in the casing and having a cross bar engaged by the head, a link hung to the cross bar, a lever pivoted to the casing, and connected to the link, and means for ex-

erting pressure on the lever, substantially as described.

8. The combination in a switch structure, of a movable tongue, a casing at one side of the structure, a rod extending laterally from the switch tongue and into the casing, a forked head secured to the rod, a rocker having hubs mounted in sockets in the casing and having a cross bar engaged by the head, 10 a link hung to the cross bar, a lever pivoted to the casing and connected to the link, means for exerting pressure on the lever, and means for adjusting the length of the link, substantially as described.

15 9. The combination in a switch structure, of a movable tongue, a casing at the side of the structure, three sets of sockets in the casing, a rocker having two pairs of hubs and a cross bar, the said cross bar being engaged 20 by a head on the rod, one of the sets of hubs being mounted in one of the sockets, and a weighted lever connected to the cross bar, said rocker being so formed that it can be shifted to rock in any of the three sockets for 25 the purpose specified.

10. The combination in a switch structure, of a movable tongue, a casing at the side of the switch structure, a rod extending into the casing, said casing having three sockets 30 at each side, a rocker having two sets of hubs and a cross bar, a weighted lever, a link hung from the cross bar and engaging the lever, a

head on the switch rod also engaging the cross bar, one set of hubs being nearer the cross bar than the other set of hubs, the 35 rocker being so designed that it can be shifted from one set of sockets to another for the purpose specified.

11. The combination in a switch structure, of a movable tongue, a rod extending from 40 the tongue, a rocker adjustably mounted in sockets in the casing, a weighted lever connected to the rocker, a hub on one side of the rocker being longer than those on the opposite side so that a rocker cannot be misplaced in the casing, substantially as described. 45

12. The combination in a switch structure, of a movable point, a casing at the side of the switch structure, sockets in the casing, a 50 rocker mounted in the said sockets, a weighted lever connected to the rocker, a rod extending laterally from the switch rod, a head on the switch rod, said head being made in two parts and adjustably mounted on the 55 rod, and shaped to engage a cross bar on the rocker, substantially as described.

In testimony whereof, I have signed my name to this specification, in the presence of two subscribing witnesses.

VICTOR ANGERER.
